UNITED STATES PATENT OFFICE.

ABRAM L. BOWER, OF BOYERTOWN, PENNSYLVANIA.

RAILWAY SIGNAL SYSTEM.

SPECIFICATION forming part of Letters Patent No. 788,513, dated May 2, 1905.

Application filed May 3, 1902. Serial No. 105,811.

To all whom it may concern:

Be it known that I, ABRAM L. BOWER, a citizen of the United States, residing at Boyertown, in the county of Berks and State of Pennsylvania, have invented a new and useful Railway Signal System, of which the following is a specification.

My invention relates to certain improvements in electric railway cab signal systems whereby the engineer of a train can receive safety, caution, or danger signals by means of a single circuit from the rails of the cab.

Applied to block-signalsystems the engineer can receive appropriate signals when a train is within three blocks in advance or in the rear. Applied to signal systems connecting with signal-towers or other signaling-points the engineer can receive the three usual kinds of signals in the manner referred to.

Figure 1 is a diagrammatic plan view illustrating the application of my invention to four blocks of a system, two of which are shown only in part. Fig. 2 is a detail view showing the manner of carrying the current to the engine-cab. Fig. 3 is an enlarged detail view showing the circuits and signal devices arranged within the cab and also the switch whereby currents can be received from either the right or left rail. Fig. 4 is a detail view of the visible signal and polarized relay for operating the same. Fig. 5 is an enlarged detail view showing two polarized relays and two drop-annunciators to indicate danger, caution, and safety signals.

In Fig. 1 I show a length of track divided into four blocks, (marked A, B, C, and D,) each of which has the same general construction of signal appliances connected thereto. The rails of each block are insulated from each other in any cases where there would be a metallic connection between the opposite side rails of the track, as in case of tie-rods, metal cross-ties, &c., and also from the rails of adjoining blocks. Every block has two signal-rails approximately fifteen feet long, more or less, which form a part of the track. These signal-rails are located about one hundred feet from the ends of the block. These signal-rails are designated A', B', C', B'', C'', and D'', respectively.

The track-rails on one side of the track and on opposite sides of the signal-rails are connected in circuit by wires A², B², C², B⁷, C⁷, and D⁷. A polarized relay and bell O on the cab receives and shows the signals. A wire P connects the bell and relay with the metallic parts of the engine. A wire J connects the bell and relay with the lever of a two-point switch I. Each of these points is connected to a metallic brush by wires G and H, the brush connected by wire G being on one side of the train and the brush connected by the wire H being on the opposite side and in contact with the rails on its respective sides. In Fig. 2 these brushes g h are shown as arranged under the center of the front coach; but it is obvious, however, that they may be carried by the engine or tender, and they are properly insulated from the train. When the engine is running in a forward direction, the switch is placed on contact-point j and when reversed on point i.

When the train is moving in a forward direction, the circuit established is as follows: from the rail to brush h, wire H, point j, switch I, wire J, relay K and the bell O, wire P and to the rails by way of the metallic parts of the engine.

When the engine is reversed, the circuit is as follows: from the rail to brush g, wire G, point i, switch I, wire J, relay K and bell O, and thence by wire P and the metallic parts of the engine to the rails. The bell may be dispensed with, if desired.

The polarized relay K is of the usual construction, but has a paddle M mounted upon the armature L and marked in three colors, preferably red for danger, white for safety, and green for caution. This paddle works behind a shutter N, having a central opening which permits the display of but one color at a time. The armature L may be held by gravity midway between the poles when the circuits are broken. A lamp M' is placed in alignment with the central opening and used in connection with the paddle M and shutter N.

The movement of the armature L is limited in either direction by the stops s and s'.

Two polarized relays may be used in the

circuit, and the stops s and s' may be replaced by contact-posts, and local circuits may be attached thereto to operate any of the usual form of annunciators or automatic drops, as shown in Fig. 5.

W and W' are colored slides, one white and one green, which are released when the magnets Q or Q' are properly energized in the manner common to annunciator-drops. Bells U and U' of the common alarm type are also shown, but may be dispensed with. A battery T is arranged in this local circuit, which also comprises the wires S and S' and the lever R and contact-point S⁴. The second local circuit contains the battery T', wires S' and S⁵, contact-point S⁵, and the lever R'.

The polarized indicator shown in Fig. 4 is to signal danger normally. A current H to J will throw the paddle M to the right, giving a safety-signal. A current in the opposite direction gives a caution-signal, and when the circuit is broken the danger-signal is displayed.

The length of the rail beyond the signal-rail is made greater than the distance between the front wheels of the train and the metallic brushes of any train, so that in no case will any part of any train receiving the signal be on the block ahead when receiving the signal. Thus it is seen that the signal-rails are set between two sections of the track proper on each block. One signal-rail is placed near one end of the block in one rail, and the other signal-rail is placed near the other end of the block, but between rails on the opposite side of the track. Considering the rails of the track in each block as forming a rectangular elongated figure, the two signal-rails of each block are arranged near diagonally opposite corners, the corner in each case being on the right side as viewed from the end of the block and looking toward the center of the block. This arrangement is necessary for the reason that the signals for a moving train are always taken from the signal-rail in the right-hand rail.

Fig. 1 illustrates a single-track system. On a double-track system the two signal-rails per block are used, as before, and are placed in the same relative position. The inner rails of each block will be continuous, and the signal-rails will be arranged in the outer rails of each track. The object of this arrangement is to have trains take signals which indicate the condition of the blocks ahead from the signal-rail of a block just before entering the block.

Signal-rails A' B' C' transmit signals to trains going in the direction of A to D and rails D' C' B' to trains going in the opposite directions. Since all the blocks are constructed alike, I will describe in detail block C only.

A battery C⁴ is connected to the two rails, its positive pole to rail C⁵ by wire 1 and its negative pole to rail C³ by wire 4. This bat-

tery operates relays L² and L⁶ and the distant relays R⁵ and R' at the ends of blocks B and D. The circuits are as follows: from battery C⁴, through wire 1, rail C⁵, wire C⁷, rail C⁵, the rail being considered as a cut rail in two sections connected by the wire C⁷, wire 2, wire 3, rail C³, and wire 4, back to the battery; from battery C⁴, through wire 1, rail C⁵, wire 5, relay L⁶, wire 6, rail C³, wire C², rail C³, and wire 4, to the battery; from battery C⁴, through wire 1, rail C⁵, wire C⁷, rail C⁵, wire 7, relay R', wire 8, rail C³, and wire 4, to battery; from battery C⁴, through wire 1, rail C⁵, wire 9, relay R⁵, wire 10, rail C³, and wire 4, to the battery. The home signals for trains leaving block C are controlled by relays L³ and L⁷, and the distant signals by relays R³ and R⁷. The circuits are as follows: from battery B⁴ of block B, through wire 11, rail B⁵, wire 12, relay L⁷, wire 13, rail B³, wire B², rail B³, and wire 14, to the battery; from battery D⁴ of block D, through wire 15, rail D⁵, wire D⁷, rail D⁵, wire 16, relay L³, wire 17, rail D³, and wire 18 to the battery; from battery A⁴ of block A through wire 19, rail A⁵, wire 20, relay R⁷, wire 21, rail A³, wire A², rail A³, wire A², rail A³, wire 22 back to the battery; from battery E⁴ of block E through wire 23, rail E⁵, wire 24, relay R³, wire 25, rail E³, and wire 26 to the battery. Where stationary signals are operated by other systems, these home relays may be operated by any of the home circuits and the distant relays and connections by any of the distant circuits.

Fig. 1 shows a normal danger system. The track-relays shown there are equipped with double armatures. The double armatures are connected by bars of insulating material 27 28 29 30 31 32 33 34 35 36 37 38, respectively. I shall designate the double armatures by the numbers of their connecting-bars. All the double armatures are either arranged below the relays or are supplied with springs which tend to draw them away from the relays, so that whenever the current from the proper track-battery is broken from a certain relay its armature will fall.

A description of the signal-transmitting mechanism in the vicinity of relays L³ and R³ will serve to explain that of the rest of the line.

Double armature 37 is equipped with two contact-points 43 and 44 and a stop 45 to limit its movement away from the point 43.

Armatures *d* and *n* are the single armatures connected by the insulated bar 37 and forming the double armature. Armature *d* is pivoted at one end and connected by wire *e* to rail C'. Its free end plays between stop 45 and contact-post 43. Armature *n* has its pivoted end connected to rail C³ by wire *l*. Its free end is in contact with post 44 when armature *d* is in contact with post 43.

Wire *c* connects post 43 with the pivoted

end of armature *b* of double armature 38, and wire *n* connects post 44 with the pivoted end of armature *o* of double armature 38.

Armature *b* plays between the contact-points 39 and 40, 39 being on the spring side and 40 on the relay side. Armature *o* plays between contact-points 41 and 42, the latter being on the relay side.

Battery *V* supplies the current for signaling to the train. Its positive pole is connected to the points 40 and 41 by wires *a* and *t*, respectively, and its negative pole is connected to points 39 and 42 by wires *r* and *p*, respectively.

Assuming that no cars are on the block A or on the block ahead of A, current will then be passing through relays *L*^s and *R*^s, and the double armatures are adjacent to the relays. The signaling-circuit is as follows: from battery *V* through wire *a*, contact-point 40, arm *b*, wire *c*, contact-point 43, arm *d*, wire *e*, signal-rail *B*⁶, wire *H*, indicator *K*, and wire *P* of the train-circuit, rail *B*⁵, wire *l*, arm *m*, contact 44, wire *n*, arm *o*, contact 42, and wire *p* to the battery *V*. As I have previously stated, a current flowing through the indicator *K* in this direction will throw the paddle to the right and show a white light.

I show a train on block B at F and one on block D at F'. Both receive caution-signals. The circuits at F are as follows: Battery *C*⁴ energizes relay *L*² and holds the armature to the relay. Battery *D*⁴ is shunted by the wheels 35 of train F', and the current does not energize relay *R*². Its armature is therefore drawn away from the relay by the spring *x*. The circuit is as follows: from battery *V* through wire *t*, contact 41, armature *o*, wire *n*, contact 44, arm *m*, wire *l*, rail *B*³, wheels F, wire *P*, indicator *K*, wire *J*, switch *I*, point *j*, wire *H*, brush *h*, rail *B*¹, wire *e*, armature *d*, contact-point 43, wire *c*, armature *b*, contact-point 39, and wire *r* to the battery. This last-described circuit will throw the paddle to the left and show a caution-signal.

If a train were leaving block C in the direction of block D, it would not receive a current from the rails and the signal would remain at "danger." The train F' shunts battery *D*⁴ and demagnetizes relay *L*³, and the armature is thrown by the spring *x* from the relay. Arms *d* and *m* have no connection with battery *V*, and the circuit to rail *C*⁴ is broken. A danger-signal is therefore displayed. These devices may be modified in many ways without departing from the spirit and scope of the invention.

What I claim as new, and desire to secure by Letters Patent, is—

1. In an electrical signaling device, the combination with a block system, of signal-rails arranged adjacent each end of a block and between track-rails on opposite sides of the track, batteries arranged in each block and

having their poles connected to opposite rails of a track, a connecting-wire leading around each signal-rail, signal devices arranged on an engine and in circuit with the track-rails, and batteries and relays in circuit with the rails 70 adapted to control the display of said signals as the train passes over said signal-rails.

2. In an electric signaling device, the combination with a block system, of signal-rails arranged adjacent each end of each block and between track-rails on opposite sides of the track and insulated from the track-rails, wires connecting the rails on sides of the signal-rails, brushes carried by a train and adapted to contact with the rails of the track and with the signal-rails, signal devices carried by the engine, a relay on the engine adapted to actuate said signal devices and normally in circuit with one of said brushes, and a plurality of batteries and relays in circuit with the 85 track-rails adapted to automatically control the circuit through said brushes and regulate the display of the signals to indicate on an engine before it leaves one block the condition of the block ahead. 90

3. In an electric signaling device, the combination with a block system, of insulated signal-rails arranged adjacent each end of each block, home and distant signal-circuits, relays controlled thereby, batteries, pole-changers 95 connecting said batteries with the signal-rails and controlled by the relays, brushes carried by a train and adapted to contact with the signal-rails, signal devices carried by the train, a relay thereon having a polarized armature 100 adapted to actuate said signal devices and normally in circuit with one of said brushes, as and for the purpose set forth.

4. In a railway signal system, the combination with a plurality of insulated blocks, insulated signal-rails arranged in each block, a plurality of pivoted, double armatures and electromagnetic relays adapted to attract said armatures, springs adapted to hold the armatures away from the relays, batteries in circuit with the track-rails, wires connecting the track-rails around the signal-rails, a wire connecting each signal-rail with one member of one double armature, a wire connecting a track-rail with the other member of the armature, a relay in circuit with the adjoining block, a double armature actuated by said relay, contact-points engaged by the first-mentioned double armature, said points being in circuit with the double armature last mentioned, contact-points adapted to be engaged by the last-mentioned armature, a battery in circuit with the last-mentioned contact-points, signal devices carried by a train adapted to be controlled by the movements of said armatures, brushes carried by the train in circuit with the signal devices on the train and adapted to contact with the track and signal rails, as and for the purpose set forth. 115 120 125

5. In a railway signal system, the combina- 130

tion with a section of track to be guarded, of insulated signal-rails arranged adjacent each end of the track-section, batteries in circuit with said signal-rails, means connected to the 5 track-section adapted to change the polarity of the batteries, signal devices arranged on an engine and in circuit with the track-rails,

and a polarized relay carried by the engine adapted to vary the signal when the polarity of the signal-rail changes.
